UNITED STATES PATENT OFFICE.

JOHN C. MACEVITT, OF BROOKLYN, NEW YORK.

FLUID-CONTROLLER.

SPECIFICATION forming part of Letters Patent No. 425,234, dated April 8, 1890.

Application filed November 8, 1887. Serial No. 254,628. (No model.)

To all whom it may concern:

Be it known that I, JOHN C. MACEVITT, a citizen of the United States, residing at Brooklyn, county of Kings, and State of New York, have invented certain new and useful Improvements in Fluid-Controllers, fully described and represented in the following specification and the accompanying drawings, forming a part of the same.

10 This invention relates to improvements in clamps for fluid-tubes.

The object of the invention is to provide a simple, inexpensive, and reliably-operative clamp for controlling the flow of a fluid 15 through a tube of flexible material.

One of the uses to which this invention is particularly applicable is in connection with nursing-bottles. It may, however, as will be readily seen, be used equally well in connection 20 with syringes, douches, irrigators, &c.

As a full understanding of the invention can be best given by an illustration and a description of the same, such description will now be given, reference being had to the accompanying drawings, in which—

Figure 1 is a side view of my improved clamp, showing the same applied to a small section or piece of tubing of flexible material. Fig. 2 is a perspective view of the clamp, and 30 Fig. 3 is a similar view of a slight modification of the same.

As shown in the drawings, the several parts of the clamp, with the exception of the slide G, are made from but a single piece of spring-wire. In the formation of these several parts a piece of spring-wire of a length suitable for the purpose is bent at a short distance from its center, so as to form the ring B, which is then bent up at about right angles to the two 40 straight long and short portions of the wire. The short portion of the wire is then bent to form the pressing-surface C and the leg F. The longer portion is then so bent as to form the leg H, pressing-surface D, and square portion E, which square portion will be at right angles to the legs F and H, and will inclose the pressing-surface C, as shown in Fig. 2, so as to prevent said pressing-surface from springing out of place. When the parts have 45 been thus formed, a slide, as G, will be fitted over the legs F and H at the ring B, where they are drawn against each other and inclose the same, as shown.

The purpose of the ring B and square portion E is to inclose the tube on which the 55 clamp is placed and keep the opposed pressing-surfaces C and D in operative position. The slide G is shown in the drawings in its normal position, or the position it will occupy when the clamp is not in use.

60 The modification shown in Fig. 3 differs from the construction just described, in that it has no square portion E.

The manner of using the clamp is as follows: When the clamp is not in use, the 65 slide G will, as before stated, occupy the position in which it is shown in the drawings. When it is desired to diminish the flow of liquid through the tube to which the clamp is attached—say to one-half the capacity of 70 the tube—the slide G will be moved along the legs F H to about midway of the length of said legs. This movement of the slide G will cause the pressing-surfaces C D to be drawn toward each other, and thereby press the tube 75 between them, and thus contract the opening through said tube. When it is desired to stop entirely the flow through the tube, the slide G will be moved up against the square portion E, when the opening through the tube 80 will be closed and no liquid will be allowed to pass through the same. To put the clamp out of operation, all that is necessary to be done is to move the slide G back against the ring B.

85 What I claim is—

1. A clamp for fluid-tubes, consisting of the legs F and H, the ring B at one extremity thereof, pressing-surfaces C D at the other extremity thereof, and the slide G, for pressing 90 said surfaces against the tube, substantially as described.

2. A clamp for fluid-tubes, consisting of the legs F and H, the ring B at one extremity thereof, pressing-surfaces C D at the other extremity thereof, square portion E, inclosing 95 said surfaces, and the slide for pressing said surfaces against the tube, substantially as described.

In testimony whereof I have hereunto set 100 my hand in the presence of two subscribing witnesses.

JOHN C. MACEVITT.

Witnesses:

DANIEL FERRY,
WM. J. HOWIE.
